US0D1033519S

(12) **United States Design Patent** (10) **Patent No.:** **US D1,033,519 S**
(45) **Date of Patent:** **** Jul. 2, 2024**

(54) **CAMERA MOUNT**

(71) Applicant: **OBDSPACE TECHNOLOGY CO., LTD**, Shenzhen (CN)

(72) Inventor: **Xiaofeng Hao**, Shenzhen (CN)

(73) Assignee: **OBDSPACE TECHNOLOGY CO., LTD**, Shenzhen (CN)

(**) Term: **15 Years**

(21) Appl. No.: **29/854,457**

(22) Filed: **Sep. 26, 2022**

(51) LOC (14) Cl. **16-05**

(52) U.S. Cl.

USPC **D16/219**

(58) **Field of Classification Search**

(57) **CLAIM**

The ornamental design for a camera mount, as shown and described.

DESCRIPTION

FIG. 1 is a perspective view of a camera mount showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The dashed broken lines shown in the drawings depict portions of camera mount that form no part of the claimed design. The dot dash broken lines represent a boundary the purpose of disclosing areas of enlargement and form no part of the claimed design.

1 Claim, 10 Drawing Sheets
